[57] CLAIM

The ornamental design for a vial holder and unit gauge for hypodermic syringes, substantially as shown and described.

DESCRIPTION

FIG. 1 is a top plan view of a vial holder and unit gauge for hypodermic syringes showing our new design;
FIG. 2 is a side elevational view;
FIG. 3 is a bottom plan view;
FIG. 4 is a one end view;
FIG. 5 is the other end view; and
FIG. 6 is a cross-sectional view taken along line 6—6 of FIG. 1.
